METHOD OF AND APPARATUS FOR CREPING PAPER

Filed June 7, 1926

UNITED STATES PATENT OFFICE.

AUSTIN E. COFRIN, OF GREEN BAY, WISCONSIN.

METHOD OF AND APPARATUS FOR CREEPING PAPER.

Application filed June 7, 1926. Serial No. 114,868.

The invention relates to a method of and apparatus for creping paper and has as an object the creping of paper as a continuous process in the manufacture thereof.

5 An illustrative embodiment of the apparatus for carrying out the process is shown in the accompanying drawing wherein the figure is a diagrammatic side view of a paper making machine showing a portion 10 only of the drying end.

As shown, the feed end of the machine is indicated at 10 and the Fourdrinier portion at 11. An upper felt 12 and a lower felt 13 are indicated receiving the web from 15 the Fourdrinier wire. The formed web is indicated at 14 as passing to the drying portion of the machine independently of the felt. In the carrying out of the present invention the web 14 is shown as pressed 20 against the first heated drying roll 15 by means of a press roll 16, which latter roll should have a smooth surface as indicated by the drawing, thus resulting in plastering the web upon the roll 15 and the adhesion 25 of the web to the roll because of its heated condition.

To crepe the paper, a doctor is indicated at 17 which acts in the well-known manner to scrape the web from the roll with a resultant creping. The creped paper is then passed to the succeeding drying rolls 18, being maintained thereagainst by belts 19, 20, in the usual manner.

By virtue of the process supplied by the invention the paper is continuously creped during the process of its manufacture and the usual additional expense of drying the paper, removing the paper from the machine, remoistening the same in order to 35 crepe is avoided. By use of the press roll 16 to plaster the paper on to drum 15 in the absence of a felt holding the web against the roll, the steam is free to leave the web, thus resulting in a more uniform and efficient adhesion of the web to the roll and the crepe that results is therefore a full crepe. The apparatus for carrying out the process can therefore be applied to existing machines with a minimum of expense.

50 The process may be carried out without use of a heated roll as at 15. However, in

such practice, the roll taking the place of roll 15 and the roll pressing the web thereagainst as at 16, would require to be made of material of different characters in order 55 to insure that the paper web would at all times adhere to the creping roll instead of to the other roll. Possible materials for the two rolls, when a heated roll is not to be used, would be wood, rubber, or material 60 of a relatively soft composition for the press roll and metal, or material which is relatively harder than the press roll for the roll to which the web is to adhere.

Minor changes may be made in the apparatus without departing from the spirit of the invention.

I claim:

1. The process of making and creping paper as a continuing process in the manufacture thereof which comprises passing the web in the condition received from the wet end of the machine between a smooth surfaced press roll and a heated roll, said rolls in direct contact with the opposite surfaces 75 of the web with consequent adhesion of the web to the heated roll, scraping the adhering web from the heated roll and passing the thus creped web to successive drying rolls. 80

2. A paper making and creping machine comprising in combination means to form a paper web, a heated roll receiving the formed web from said first named means, a smooth surfaced press roll adapted to contact directly with said web to plaster the 85 web upon the surface of the heated roll, a doctor to scrape the web from the heated roll with resultant creping thereof and means to dry the creped web.

3. In the making and creping of paper as a continuous process the method which comprises passing the web in the condition received from the wet end of the machine between and in direct contact with a creping roll and a smooth surfaced press roll, said 95 rolls having differing characteristics such as to cause the web to adhere to the creping roll, scraping the web from the creping roll and passing the thus creped web to the drying end of the machine.

AUSTIN E. COFRIN.
